BALL WINDING MACHINE

Henry Z. Cobb, Providence, R. I., assignor, by
mesne assignments, to United States Rubber
Company, New York, N. Y., a corporation of
New Jersey

Application April 10, 1934, Serial No. 719,861

8 Claims. (Cl. 242—3)

My invention relates to ball winding machines, and more particularly to machines for winding golf balls with relatively wide tape.

In ball winding machines of the type shown in the Worthington Patent 740,348 difficulty is encountered if an attempt is made to wind wide tape, that is tape of a width of the order of half an inch or more. Such tape has a tendency to follow the curvature of the ball toward the side thereof and ultimately escape laterally of the ball rather than conform to the previously wound portion of the ball. With increasing widths of tape the tendency becomes more and more pronounced.

In order to avoid such misalignment or crawling of the tape as it is applied to the ball, I provide a pressure wheel which extends between the winding discs and continuously engages the periphery of the ball during its movement between the winding discs. The tape being applied to the ball is passed around the pressure wheel so that the tape is always delivered centrally and tangentially of the ball regardless of the position of the ball within the winding discs. By insuring that the tape is applied centrally of the ball the tendency of the tape to crowd or crawl to the side of the ball is eliminated and a satisfactorily wound ball using relatively wide tapes is obtained.

The pressure wheel is made relatively narrow to fit between the faces of the discs when a ball core is initially inserted therebetween. It is also made of sufficient diameter so that it can ride up and down in the space between the faces of the winding discs without interference between its support and the edges of the disc.

By reason of the up and down movement of the core and winding between the winding discs there is an irregular pull on the tape. This irregular pull is sufficiently severe to cause overrunning of a tape roll and the occasional snapping of tape unless means are provided for tensioning the tape as it is fed. For tensioning the tape it is fed around at least a semi-circumference of the pressure wheel and is led between pinch rolls one of which is provided with a brake and a rubberized gripping surface to prevent slippage of the tape. Means are provided for properly centering the tape relative to the pinch rolls.

The winding discs are driven through differential gearing from a motor. Means are provided for controlling the amount of tape wound upon a ball by stopping the motor at the end of a predetermined separation of the winding discs.

The accompanying drawings illustrate a present preferred embodiment of the invention, in which

Fig. 1 is a front elevational view, partly in section, of the winding machine;

Fig. 2 is a diagrammatic view, partially in elevation and partially in section, showing the winding discs and their yieldable mountings;

Fig. 3 is a view of a wound ball, before the application of the cover, the core being shown in dotted circular outline and the convolutions of the tape being shown in full lines;

Fig. 4 is a cross sectional view of the machine along a section line IV—IV of Fig. 1;

Fig. 5 is a plan view, partially in elevation and partially in section, of the machine bed plate and parts located therebeneath and taken substantially along the section line V—V of Fig. 4; and

Fig. 6 is a detail view of a portion of the supporting mechanism for the pressure wheel.

Referring to the drawings the ball winding machine comprises oppositely disposed winding discs 2 and 3 which are provided with complementary grooves 4 in which a ball core is placed for being wound with tape. The discs 2 and 3 are illustrated in Fig. 2 as comprising hard rubber wear faces 6 in which the grooves 4 are cut. The wear surfaces are attached to the discs proper by suitable securing means such as set screws 7. The rubber composition in the faces 6 may be varied considerably, but I prefer a composition which, when vulcanized, is sufficiently hard to withstand lateral pressure to maintain the shapes of the grooves 4 but still of sufficient resiliency to be slightly yielding for equalizing wear in the grooves.

The disc 2 is mounted on a shaft 8 resting in bearings 9 on a bedplate 10. The shaft 8 is longitudinally movable in the bearings 9 by means of a collar 11 pinned thereto. The collar 11 cooperates with a yoke 12 for shifting the shaft 8 longitudinally. A driving gear 14 is secured at the end of the shaft by a clamping nut 15. The disc 3 is likewise supported by a shaft 16 in bearings 9. The shaft 16 is provided with a similar collar 11 and yoke 12 and a driving gear 17.

The gears 14 and 17 are connected through intermediate gears 18—19, and 20—21, respectively, with a drive shaft 22 carried in bearings 24 suspended from the bedplate 10. The intermediate gears 18 and 20 are carried on stub shafts 25 riveted or otherwise secured to adjustable side plates 26 mounted on the ends of the bedplate 10.

As shown in Figs. 4 and 5, the ends of each of the plates 26 are slotted to receive clamping bolts 27 so that the plates may be removed or adjusted if it is desired to change the gears 18 and/or 20. Preferably, the gear trains 14-18-19 and 17-20-21 are different so that the discs 2 and 3 revolve at different speeds to give the required rolling motion to a ball core disposed in the grooves 4.

- 11 The shaft 22 is driven from a motor 28 through a gear train 29-30, the gear 30 being keyed to the shaft 22.

Referring particularly to Figs. 1 and 2, the discs 2 and 3 are normally urged toward each other by a weight 31 which is connected by a link 32 to one end of a lever 34. The lever 34 is pivotally mounted at 35 in an arm 36 which is suspended from the bedplate 10 by a bracket 37. The lever 34 is pivotally connected at 38 to a rod 39 extending upwardly through the bracket 37 and having longitudinal movement therein. The bracket 37 is provided with a cutaway portion 40 in which a collar 41 is disposed about and secured to the rod 39. Yoke arms 42 and 44 cooperate with the collar 41 and are attached to stub shafts 45 and 46, respectively. The shafts 45 and 46 are supported by brackets 47 and 48, respectively, extending downwardly from the bedplate 10. The yokes 42 cooperating with the collars 41 are attached to the shafts 45 and 46 so that as the weight 31 tends to move downwardly under the influence of the force of gravity, the rod 39 is pulled downwardly to rotate the shafts 45 and 46 to move the shafts 8 and 16 longitudinally to bring the discs 2 and 3 toward each other. As the weight 31 is always present, a uniform yielding pressure is exerted by the discs on a ball being wound therebetween.

For opposing the weight 31 and for separating the discs 2 and 3, a link 49 depends from the end of the lever 34 opposite link 32 and is connected to a foot pedal, not shown. By depressing the link 49 the lever 34 is turned in a clockwise direction to raise the rod 39 and thereby separate the discs 2 and 3.

As wide tape of the order of one-half inch in width tends to slip or crawl off the sides of a ball being wound in the machine of the Worthington Patent 740,348, I have found that proper winding of wide tape can be had by placing a pressure wheel 50 in the space between the faces of the discs 2 and 3 so as to be in continuous engagement with a ball 51 being wound therebetween. The surface 52 of the wheel 50 is preferably curved to conform to the shape of the ball. A tape 54 is led around the wheel 50 substantially a semi-circumference so that the tape is discharged centrally and tangentially of the ball 51 regardless of the position of the ball in the grooves 4 between the discs 2 and 3. In order to permit the wheel 50 to follow the ball it must be at least as narrow as the minimum separation of the discs at the initiation of a winding operation. Stated in another way, the thickness of the wheel 50 must not exceed the spacing of the faces of the discs 2 and 3 when a core, shown by the dotted circular 55, Fig. 3, is initially placed between the discs 2 and 3. The wheel 50 must also be of such a diameter that it can ride from the uppermost position of the ball between the discs, as shown in Figs. 1 and 4, to the lowermost position, as shown in Fig. 2. Accordingly, the radius of the wheel should be made sufficiently great so that the wheel hub 56 and the supporting shaft

57 are always above the outer edges of the discs 2 and 3.

The shaft 57 is supported by an arm 58 fulcrumed at 59 to a bracket 60 bolted or otherwise secured to the bedplate 10. A spring 61 is attached between a bracket 62 secured by bolts 64 to the bedplate 10, and an opening 65 in the arm 58. Accordingly, the wheel 50 is held in engagement with the ball 51 by a uniform pressure regardless of the position of the ball in the grooves 10 4 between the discs 2 and 3.

Referring particularly to Fig. 6, the arm 58 extends through a slot 66 in a guide 67. For holding the wheel 50 in inoperative position, a latch 68 is pivoted at 69 to the guide 67. The latch 15 is normally held in a position to project into the slot 66 by a spring 70 secured between the guide 67 and a pin 71 on the latch. Stop pins 72 and 74 limit the inward and outward movement. Accordingly, the wheel 50 is raised into inoperative 20 position by raising the arm 58 above the latch 68. To restore the wheel 50 to operative position the latch 68 is withdrawn from the slot 66 and the arm is permitted to drop.

To insure that the winding operation will cease 25 when the ball is sufficiently wound, as determined by the separation of the discs 2 and 3, a switch 75 shown in Fig. 4 is interposed in the circuit of the motor 28. The switch 75 comprises a housing 76 for a stationary contact member 77 and a movable 30 contact member 78.

The contact member 78 is carried by and insulated from an arm 79 pivoted to a bracket 80 mounted on the bedplate 10. A spring 81 normally tends to keep the contact member 78 in 35 engagement with the contact member 77.

A screw 82 is carried on the end of the arm 79 and is in alignment with a head 84 on a rod 85 projecting upwardly through a sleeve 86 mounted in the bedplate 10. As shown in Fig. 2 the rod 85 40 is attached to the lever 34 by a pin 87 so that as the lever is raised during the separation of the discs 2 and 3, the head 84 approaches the screw 82. When the head 84 engages the screw 82, continued upward movement of the head 84 breaks 45 the circuit between the contact members 76 and 77 thereby interrupting the circuit of the motor 28. When the head 84 is again lowered the circuit of the switch 75 is again completed.

Owing to the variations in the position of the 50 ball 51 in the grooves 4 there is a variation in the tension on the tape 54. In order to properly tension the tape it is passed around a semi-circumference of the wheel 50 and around a portion of the surface of a tensioning wheel 88 which, 55 preferably, is provided with a rubber gripping surface 89 and between the tensioning wheel 88 and a pinch roller 90 which may also be provided with a rubber gripping surface 91. The tape is supplied from a spool 92 and passes over a roller 60 94 and under a roller 95 from which it is led to the pinch roller 94. The roller 95 is adjustably mounted by a screw 96 so that it may be centered relative to the pinch roller 90 and the wheel 88. The wheel 88 is pivotally supported by straps 97 65 on a shaft 98 so that it bears against the tape by gravity. A brake 99 passes around a brake drum 100 on the wheel 88. A spring 101 tensions the brake 99.

In operating the machine the operator takes a 70 ball core of any suitable material, many of which are used in the manufacture of golf balls, or forms a core by rolling a little tape into a bunch. If the core is used a few wraps of tape are made around the core. The pressure wheel 50 is then 75

in its elevated position. The operator presses the pedal to separate the discs 2 and 3 and inserts the core. The wheel 50 is then lowered and the pedal released to complete the circuit of the motor 5 through the switch 75. The motor starts to spin and the discs 2 and 3 rotate to give the required winding motion to the ball 51. At the end of the proper time the discs are separated sufficiently to open the switch 75 and stop the motor. The operator then breaks the tape 54 and binds the end of the tape, preferably, by inserting the loose end under some of the previous convolutions of the tape and the ball is removed preparatory to a covering or other finishing operation. The cycle 10 of operations is repeated.

While I have shown and described a present preferred embodiment of my invention, it is to be understood that it may be otherwise embodied within the spirit of the invention and the scope 15 of the appended claims.

Having thus described my invention, what I claim and desire to protect by Letters Patent is:

1. In a ball winding machine, a pair of rotatable discs having cooperating grooved faces between 25 which a ball is wound, and a thin pressure wheel mounted in the plane of the opening between the discs to float in engagement with a ball between said discs during the winding operation and as the ball assumes different positions relative to said discs.

2. In a ball winding machine, a pair of rotatable discs having cooperating grooved faces between which a ball is wound, a pressure wheel mounted with its axis parallel to the axis of the discs to 35 float in engagement with a ball between said discs during the winding operation and as the ball assumes different positions relative to said discs, and means for applying uniform pressure to said wheel.

3. In a ball winding machine, a pair of rotatable discs having cooperating grooved faces between which a ball is wound, a pressure wheel mounted to float between the discs and across the axis thereof while in engagement with a ball between 45 said discs during the winding operation and as the ball assumes different positions relative to

the axis of said discs, a supporting arm for said wheel, and means for applying a constant pressure to said wheel.

4. In a ball winding machine, a pair of rotatable discs having cooperating grooved faces between 5 which a ball is wound, a pressure wheel mounted to float in engagement with a ball between said discs during the winding operation and as the ball assumes different positions relative to said discs, a supporting arm for said wheel, means for applying a constant pressure to said wheel, and a latching means for holding the wheel in inoperative 10 position.

5. In a ball winding machine, a pair of cooperating winding discs between which a ball is 15 wound, a pressure wheel extending between the faces of said discs for engaging a ball during the winding operation and feeding tape thereto under uniform conditions of pressure and direction, and means for supplying tape to said wheel 20 under uniform tension.

6. In a ball winding machine, a pair of cooperating winding discs between which a ball is wound, a pressure wheel extending between the faces of said discs for engaging a ball during the 25 winding operation and feeding tape thereto under uniform conditions of pressure and direction, and means for supplying tape to said wheel under uniform tension, said supplying means comprising a tension wheel about which the tape passes 30 on its way to the pressure wheel.

7. In a ball winding machine, a pair of rotating winding discs, yieldable mountings therefor, and a thin wheel extending between said discs and engaging a ball wound therebetween, said wheel being of sufficient diameter so that the wheel can 35 follow the ball in its movement between said discs without interference from supporting means for the wheel and the discs.

8. In a ball winding machine, a pair of yield- 40 ably mounted rotatable winding discs, and a pressure wheel adapted to bear on a ball being wound between said discs, the periphery of said wheel being curved to conform to the shape of the ball as it is wound.

HENRY Z. COBB.
